(57) **CLAIM**

The ornamental design for a bra, as shown and described.

DESCRIPTION

FIG. 1 is a front elevational view of a bra showing my new design;

FIG. 2 is a rear elevational view thereof;

FIG. 3 is a perspective view thereof;

FIG. 4 is a front elevational view of the bra in FIG. 1 shown on a human body;

FIG. 5 is a rear elevational view thereof; and,

FIG. 6 is a perspective view thereof.

The broken lines showing portions of the human form in FIGS. 4-6 show the bra in use, and form no part of the claimed design.

The broken lines, throughout the views, on the surface of the bra represent stitching.
